CLAIM

The ornamental design for seat, as shown and described.

DESCRIPTION

FIG. 1 is a perspective view taken from the top, front and left side of a seat embodying my new design in the form of a chair;

FIG. 2 is a front elevational view thereof;

FIG. 3 is a rear elevational view thereof;

FIG. 4 is a left side elevational view thereof, the right side elevational view being the mirror image thereof;

FIG. 5 is a top plan view thereof;

FIG. 6 is a bottom plan view thereof;

FIG. 7 is a perspective view taken from the top, front and left side of a second embodiment of my new design in the form of a chair wherein the difference is substantially a matter of length.

FIG. 8 is a front elevational view thereof;

FIG. 9 is a rear elevational view thereof;

FIG. 10 is a left side elevational view thereof, the right side elevational view being the mirror image thereof;

FIG. 11 is a top plan view thereof; and

FIG. 12 is a bottom plan view thereof

FIG. 13 is a perspective view taken from the top, front and left side of a third embodiment of my new design in the form of a sofa wherein the difference is substantially a matter of length and an additional support member.

FIG. 14 is a front elevational view thereof;

FIG. 15 is a rear elevational view thereof;

FIG. 16 is a left side elevational view thereof, the right side elevational view being the mirror image thereof;

FIG. 17 is a top plan view thereof; and,

FIG. 18 is a bottom plan view thereof.
